UNITED STATES PATENT OFFICE.

ERNEST F. HARTMANN, OF NEW YORK, N. Y.

APPARATUS FOR TREATING TIMBER.

1,240,443.

Specification of Letters Patent.

Patented Sept. 18, 1917.

Application filed February 20, 1917. Serial No. 149,879.

To all whom it may concern:

Be it known that I, ERNEST F. HARTMANN, a citizen of the United States, residing at New York city, New York, have invented certain new and useful Improvements in Apparatus for Treating Timber, of which the following is a clear, full, and exact description.

10 The present invention relates to an apparatus for treating timbers with a suitable wood preserving fluid, and in my preferred embodiment shown, is more particularly adapted for forcing fluid under pressure into the upper ends of driven-in piles.

15 By forcing the wood preserving material into the end of the pile, it will follow the grain of the wood and by a continuation of the treatment, the pile may be impregnated as far along its length as may be desired.

20 A further object of the invention is to provide an apparatus which may be employed for treating piles of various diameter and of irregular contour. The present apparatus is designed for embracing only a portion of the pile at a time, and therefore I have devised novel and improved means for hermetically and securely sealing the joint between the end of the apparatus and the sides of the pile.

25 Further objects of the invention will become apparent from the following description when taken in connection with the accompanying drawings, which show the preferred embodiment of the invention, and in which—

30 Figure 1 shows the upper end of a pile with the apparatus mounted on the same, shown in section taken along line 1—1 of Fig. 2;

35 Fig. 2 is a horizontal section through the apparatus along line 2—2 of Fig. 1;

40 Fig. 3 is a further horizontal section through the pile and the apparatus along line 3—3 of Fig. 1;

45 Fig. 4 is a detail section through a portion of the collar, along line 4—4 of Fig. 2;

Fig. 5 is a detail perspective of one of the collar sections;

50 Fig. 6 is a detail perspective of the lower end of a fastening bolt; and

Fig. 7 is a plan view of a collar section of larger size.

Referring more particularly to the drawings, the upper end of the pile to be treated

is indicated at 1. Adapted to encircle the pile a convenient distance from its upper end, is an adjustable collar 2 made up of separate sections adapted to be detachably fastened together by suitable bolts 3. As shown in Figs. 4 and 5, the collar sections are like Z bars in cross section with a lower inner wall 4 having pointed projections or picks 5 for being embedded into the timber, a horizontal shoulder or seat 6 for supporting the joint sealing material herein-after described, and an outer vertical wall 7 for retaining said sealing material on the shoulder. The abutting end flanges 8 of said sections have suitable perforations 9 for receiving the fastening bolts 3. It is understood that the collar sections through their adjustable connecting bolts 3 may be fitted tightly around piles of different diameters and of uneven contour and firmly anchored in place. Furthermore, in order to increase or decrease the circumference of the assembled collar, larger or smaller sections may be substituted for those shown in Fig. 3. Such a larger section is shown at 2' in Fig. 7. The gaps between the ends of any two sections are preferably bridged by shims, such as shown at 10, 11, Figs. 2, 3 and 4. These shims are in the form of thin angle pieces with a bottom side 11 adapted to rest flat upon the horizontal shoulder 6 of the collar and with a curved vertical wall 10 for resting against the wall 7 of the collar.

Located above the collar 2 is a timber-embracing member comprising a head 12 with depending side walls 13 adapted to surround and embrace the upper end of the pile 1. In the embodiment shown, the timber-embracing member is shaped like a cylindrical cap member for fitting over the top of a cylindrical pile, and the lower end of the walls 13 are flared outwardly as at 14, and are preferably supported upon the horizontal shoulder 11 of the collar 2. An inlet pipe 15 leads through the side wall 13 into the interior of said cap member, said communication being controlled by an ordinary hand valve such as 16, whereby wood preserving fluid may be introduced into the space between the cap member and the pile under pressure during the period of impregnation of said pile and may also be drained out of said space when the treatment is finished.

2

ished. 17 indicates an air valve through the head of the cap member, whereby air may be released from within the cap member during the introduction of oil and whereby air under pressure may be admitted to within the cap member after the treatment is finished for driving out the wood treating fluid through pipe 15. 18 indicates a temperature well carried in the head 12 and extending downwardly into the space between said head and the top of the pile so that the temperature of the fluid within said space may be recorded. 19 indicates a heating coil preferably supported on brackets 20 in the head 12 for heating the space between the head and the pile and the timber treating fluid therein, and 21 indicates a protecting grid 22 to the inner sides of the cap member, whereby the said cap member will be limited in its movement down over the top of the pile and thus protect the heating coil from injury during mounting of the cap member.

It will be understood that when the adjustable collar has been firmly secured to the pile, and the cap member for embracing the top end of the pile has been placed in the position as shown in Fig. 1, means must be provided for hermetically sealing all outlets at the joint between the cap member and the sides of the pile to prevent the escape of air or fluid and also support said joint in such a way as to prevent the same from breaking loose under the force of the subsequent impregnating pressure. In the present embodiment I have obtained this seal for the joint by locating a continuous ring of plastic material between the lower end of the side walls 13 of the cap member and the pile 1, and locking the cap member with the collar firmly together so as to securely support said sealing ring.

I prefer to employ plaster of Paris for the joint sealing material and for this purpose it is poured into the collar 2 around the pile while in a plastic condition, so as to fill all crevices and openings from the space within the cap member. Any crevices too large for being automatically plugged up by the plastic plaster of Paris may be stuffed with paper or cotton waste to support the plaster until it hardens. The plaster of Paris may be poured into the space between the collar 2 and the pile, either before or after the cap member is mounted.

The cap member may be firmly locked to the collar preferably by means of a series of bolts 23, evenly distributed around the pile, and having hooks 24 at their lower end for engaging beneath ribs 25 at the outer edge of the collar shoulder. The upper ends of the bolts 23 extend through enlarged perforations 26 in the head 12 and are screw-threaded for receiving hand-wheel nuts 27 which may be turned for tightening and

drawing up on said bolts. 28 is a grasping ring upon the head of the cap member, whereby the same may be handled.

The operation of the apparatus is as follows. After the plaster of Paris in its liquid state is poured into the collar 2 and between the pile, and the cap member and the latter is securely locked to the collar as above described, the plaster of Paris is allowed to set and harden so as to make a substantially hermetically sealed joint between the sides of the timber and the walls 13 of the cap member. Thereupon the wood-treating fluid may be introduced through the pipe 15 under pressure, and the treatment continued to impregnate the timber as far as may be desired. After the treatment is finished, the space between the cap member and the pile may be drained of wood treating fluid out through the pipe 15. The collar 2 may then be removed by loosening the bolts 23 and the cap member elevated to pull away its walls 13 from the plaster seal. The lower ends 14 of the walls 13 are flared outwardly as shown, so as to facilitate this breaking away from the plaster seal.

It will be obvious that a portion of a pile or timber intermediate the ends may be similarly treated, in which case the timber embracing member will be in the form of a cylinder open at each end, which ends will be closed around the timber by means of a detachable and adjustable collar as above described.

It is also obvious that various other changes and adaptations of the broad idea here disclosed may be adopted without varying the nature of the invention or departing from the scope thereof as expressed in the appended claims.

What I claim is:

1. In an apparatus for treating timber in combination, a timber-embracing member having side walls surrounding said timber, a collar for encircling said timber adjacent the end of said side walls, means for locking said side walls and collar together, plastic material which has set and hardened supported by said collar for closing the outlet from between said side walls and said timber, and an inlet for introducing timber treating fluid under pressure to the space between said timber and said embracing member.

2. In an apparatus for treating timber in combination, a timber-embracing member having side walls surrounding said timber, a collar for encircling said timber adjacent the end of said side walls, means for locking said side walls and collar together comprising a series of fastening bolts evenly distributed around said timber, plastic material which has set and hardened supported by said collar for closing the outlet from between said side walls and said timber, and

- an inlet for introducing timber treating fluid under pressure to the space between said timber and said embracing member.
3. In an apparatus for treating timber in combination, a timber-embracing member having side walls surrounding said timber, a collar for encircling said timber adjacent the end of said side walls, and having an anchored engagement with said timber, plastic material which has set and hardened supported by said collar for closing the outlet from between said side walls and said timber, and an inlet for introducing timber treating fluid under pressure to the space between said timber and said embracing member.
4. In an apparatus for treating timber in combination, a timber-embracing member having side walls surrounding said timber, a collar for encircling said timber adjacent the end of said side walls, means for locking said side walls and collar together, plastic material which has set and hardened supported by said collar for closing the outlet from between said side walls and said timber, and an inlet for introducing timber treating fluid under pressure to the space between said timber and said embracing member.
5. In an apparatus for treating timber in combination, a timber-embracing member having side walls surrounding said timber, plastic material which has set and hardened between said side walls and said timber for closing the outlet from the space therebetween, and an inlet for introducing timber treating fluid under pressure to said space between said timber and said embracing member.
6. In an apparatus for treating timber in combination, a timber-embracing member having side walls surrounding said timber, plastic material which has set and hardened between said side walls and said timber for closing the outlet from the space therebetween, a collar for supporting said plastic material while setting, and an inlet for introducing timber treating fluid under pressure to said space between said timber and said embracing member.
7. In an apparatus for treating timber in combination, a timber-embracing member having side walls surrounding said timber, plastic material which has set and hardened between said side walls and said timber for closing the outlet from the space therebetween, a collar made up of sectional parts for supporting said plastic material while setting, and an inlet for introducing timber treating fluid under pressure to said space between said timber and said embracing member.
8. In an apparatus for treating timber in combination, a timber-embracing member having side walls surrounding said timber, plastic material which has set and hardened between said side walls and said timber for closing the outlet from the space therebetween, a collar made up of sectional parts for supporting said plastic material while setting, and an inlet for introducing timber treating fluid under pressure to said space between said timber and said embracing member.
9. In an apparatus for treating timber in combination, a timber-embracing member having side walls surrounding said timber, plastic material which has set and hardened between said side walls and said timber for closing the outlet from the space therebetween, a collar made up of sectional parts detachably fastened together for supporting said plastic material while setting, and an inlet for introducing timber treating fluid under pressure to said space between said timber and said embracing member.
10. In an apparatus for treating timber in combination, a timber-embracing member having side walls surrounding said timber, plastic material which has set and hardened between said side walls and said timber for closing the outlet from the space therebetween, a collar made up of sectional parts, detachably fastened together for supporting said plastic material while setting, and an inlet for introducing timber treating fluid under pressure to said space between said timber and said embracing member.
11. In an apparatus for treating timber in combination, a timber-embracing member having side walls surrounding said timber, said side walls terminating in an outwardly flared end and plastic material which has set and hardened constituting a seal between said flared end of the side walls and said timber, and an inlet for introducing timber treating fluid under pressure to the space between said timber and said embracing member.
12. In an apparatus for treating timber in combination, a timber-embracing member comprising a head and side walls for surrounding said timber, heating means beneath said head, plastic material which has set and hardened between said side walls and said timber for closing the outlet from the space therebetween, and an inlet for introducing timber treating fluid under pressure to the space between said timber and said embracing member.
13. In an apparatus for treating timber in combination, a timber-embracing member comprising a head and side walls for surrounding said timber, heating means beneath said head, a timber abutting member beneath said heating means, plastic material which has set and hardened between said side walls and said timber for closing the outlet from the space therebetween, and an inlet for introducing timber treating fluid under pressure to the space between said timber and said embracing member.

1,240,443

4
inlet for introducing timber treating fluid under pressure to the space between said timber and said embracing member.

14. In an apparatus for treating timber in combination, a timber-embracing member comprising a head and side walls for surrounding said timber, plastic material which has set and hardened between said

side walls and said timber for closing the outlet from the space therebetween, a fluid 10 conducting pipe extending through said side walls near the lower end thereof but above said plaster seal.

Signed at New York, N. Y., this 10th day of February 1917.

ERNEST F. HARTMANN.
